SIDEREAL-CIVIL CLOCK COMBINATION
AND CARRYING CASE THEREFOR

John P. V. Heinmuller, New York, N. Y.

Application January 7, 1931. Serial No. 507,079

4 Claims. (Cl. 58—105)

My present invention relates to chronometers and to mountings or containers for the same, and aims to devise containers or mountings for chronometers, particularly for a plurality of the same, such as one giving readings of mean solar or similar time and another giving readings of sidereal time, which devices are simple in construction, may be readily and conveniently fabricated and assembled, which are very satisfactory as mountings or containers for chronometers, which safely and securely house such chronometers, and which permits the convenient inspection of such chronometers as desired, even under difficult conditions, such as which have been met with, for example, in aviation. Other objects and advantages of the devices of the present invention will in part be pointed out in detail hereinafter and will in part be obvious to those skilled in the art to which the present invention relates.

In the accompanying specification I shall describe and in the annexed drawings more or less diagrammatically exemplify, an illustrative embodiment of the present invention. It is, however, to be clearly understood that my invention is not limited to the specific embodiment thereof herein shown and described for purposes of illustration only.

Referring to the drawings, in which I have more or less diagrammatically exemplified the aforesaid illustrative embodiment of the present invention:

Fig. 1 is a plan view of the mounting or container of the present invention in closed position with the dial or face of one of the chronometers covered by the slide;

Fig. 2 is a plan view of the mounting or container shown in Fig. 1 of the drawings in closed position with the dial or face of the remaining chronometer covered by the slide;

Fig. 3 is a plan view of the mounting or container of Figs. 1 and 2 of the drawings in open position and with one of the trays removed to make the construction of the device clearer; and Fig. 3a is a longitudinal sectional view taken on line 3a—3a of Fig. 3.

Referring now to the aforesaid illustrative embodiment of the present invention, and with particular reference to the various figures of the drawings illustrating the same, 10 indicates generally the mounting or container for the chronometers in accordance with the principles of the present invention. Said mounting or container, generally designated by reference character 10, is preferably in the nature of a box having

a main portion 11 and a cover portion 12 suitably secured thereto, as by means of the hinges 13 and 14.

The bottom of the main container portion 11 is provided with shock absorbing or cushioning plate 15 having the raised side strips 16 and 17 connected at the tops thereof with a similar longitudinal raised strip 18. The plate 15 is further provided with a central inverted T-shaped raised strip 19 having a T-portion presenting projections 20 and 21 while the lower ends of the strips 16 and 17 are turned in to present projections 22 and 23 in a line with the T-projections 20 and 21.

The plate 15 and its associated strips and projections are made preferably of a resilient material such as sponge, rubber or the like and the entire shock absorbing or cushioning means is of integral construction.

The strips 16, 17, 18 and 19 and the projections 20, 21, 22 and 23 are so arranged as to present a pair of rectangular pockets 24 and 25 by the former members and a pair of pockets 26 and 27 by the latter members, the last mentioned pockets comprising continuations of the previously mentioned pockets 24 and 25. The purposes of these pockets will become apparent from the following description.

The pockets 24 and 25 are respectively receptive of trays 28 and 29. Since the trays 28 and 29 are substantially identical, it will be sufficient for the purposes of the present description to describe only one of such trays in detail. Each tray comprises a main body portion 30 having a well or recess 31 for receiving the chronometer 32. The recess 31 is provided with the channelled portion 33 so as to receive the stem 33' of the chronometer 32, the stem 33' extending into the stem-receiving pockets 26 or 27, as the case may be.

Turning now to the cover 12 which, as already stated, is hinged to the main box or container portion 11 by means of the hinges 13 and 14, the same comprises the end walls 34 and 35, the forward wall 36 and the rear wall 37.

The cover is provided with a second shock-absorbing or cushioning means consisting of a pair of wooden walls 38 intermediate which is secured a thin resilient block 39 made of sponge, rubber or the like. The walls 38 and block 39 having recesses or ports 40 and 41 in register with the chronometer dials carried in the lower, main housing 11, the ports in the upper one of the walls 38 being bevelled at 42 to properly receive the faces of the chronometers referred to. These

same upper walls 38 are also provided with channels 43 receptive of the stems 33' of the chronometers when the carriers of the present invention are in their normally closed condition.

5 Intermediate the upper one of the walls 38 and the upper frame portion 44 of the cover 12 is a glass plate 45 permitting observation of the chronometers through the ports 40 and 41 as will hereinafter be more fully understood. It 10 may here be stated that the chronometer 32 to the left in the various figures of the drawings is a chronometer giving readings of mean solar or civil time, while the chronometer to the right in the various figures of the drawings is a chronometer giving readings of sidereal time, the former useful for longitude readings by day by the use of the sun or the moon, if visible, and the latter for readings by night by means of the stars.

15 20 The walls or frame 44 may be grooved to receive a slide 46 which during the day time may be moved to cover up the port 41 corresponding to the sidereal chronometer and during the night time may be moved to cover up the port 40 covering the mean solar or civil time chronometer, so only the appropriate chronometer will be visible at the time a particular observation is made.

25 This completes the description of the aforesaid illustrative embodiment of the present invention. The manner of constructing and assembling said embodiment will, it is believed, clearly appear from the foregoing description. Likewise the manner of using the chronometer mounting and associated chronometers of the 30 present invention will, it is believed, clearly appear from the foregoing description but may be briefly summarized as follows: Assuming that an observation is intended to be made of longitude, for example, during the day time, the slide 46 is moved to cover the observation port 41 over the sidereal chronometer and the desired observation is then made with the aid of the time reading on the mean solar or civil chronometer. Such observations are made by it in the usual 35 manner as will be readily apparent to those skilled in the art to which the present invention relates. On the other hand, should it be desired to make an observation of longitude or the like by night, the slide 46 will be moved back to expose the observation port 41 over the sidereal chronometer and to cover up the observation port 40 over the mean solar or civil time chronometer. The desired observation will then be made by means of the sidereal chronometer in 40 45 50 55 the usual way, as will be readily apparent to those skilled in the art to which the present invention relates.

60 It will be noted that the devices of the present

65

70

75

invention are compact, convenient to use and provide the necessary protection for such delicate instruments as chronometers. In order that the chronometers may be all the more securely retained in the mounting 10, I may provide suitable locking means, such as the catches 47 and 48 on the under surface of the outer portion 36 of the cover 12 and the locking means 47' and 48' associated with the forward portion of the main container portion 11, 47'' and 48'' comprising releasing means for the locking mechanisms 47' and 48', respectively, in a manner which will be readily apparent to those skilled in the art to which the present invention relates. 80 85 90

Other superiorities and advantages of the devices of the present invention in mode of construction, operation and use, will readily occur to those skilled in the art to which the present invention relates.

95 What I claim as my invention is:

1. A container for chronometers, comprising a main container portion, a plurality of chronometer trays side by side within said main container portion, a cover for said main container portion, and an opaque slide carried in said cover for covering one or the other of the chronometers, while exposing the remaining one of the chronometers.

105 2. A container for chronometers, comprising a main container portion, a plurality of chronometer trays side by side within said main container portion, a cover for said main container portion, a glass in said cover through which chronometer readings may be made, and an opaque slide in said cover for covering the portion of said glass corresponding to one or the other of the chronometers, while exposing the portion of said glass corresponding to the other chronometer.

110 115 120 3. A container for chronometers, comprising a main container portion, a plurality of removable chronometer trays side by side within said main container portion, a cover for said main container portion, and an opaque slide carried in said cover for covering one or the other of the chronometers, while exposing the remaining one of the chronometers.

125 130 135 4. A container for chronometers, comprising a main container portion, a plurality of removable chronometer trays side by side within said main container portion, a cover for said main container portion, a glass in said cover through which chronometer readings may be made, and an opaque slide in said cover for covering the portion of said glass corresponding to one or the other of the chronometers, while exposing the portion of said glass corresponding to the other chronometer.

JOHN P. V. HEINMULLER.
